(57) **CLAIM**

The ornamental design for a writing instrument, as shown and described.

DESCRIPTION

FIG. 1 is a right front perspective view of a writing instrument, showing my new design;

FIG. 2 is a front elevational view;

FIG. 3 is a rear elevational view;

FIG. 4 is a left side elevational view;

FIG. 5 is a right side elevational view;

FIG. 6 is a bottom plan view;

FIG. 7 is a top plan view;

FIG. 8 is a left front perspective view with the top portion in an opened condition;

FIG. 9 is a front elevational view of FIG. 8;

FIG. 10 is a rear elevational view of FIG. 8;

FIG. 11 is a left side elevational view of FIG. 8;

FIG. 12 is a right side elevational view of FIG. 8;

FIG. 13 is a bottom plan view of FIG. 8; and,

FIG. 14 is a top plan view of FIG. 8.

The portions of the writing instrument depicted by means of broken lines have been shown for illustrative purposes only and form no part of the claimed design.
